Application July 29, 1937, Serial No. 156,307

9 Claims. (Cl. 33—41)

This invention relates to scribes and more particularly to scribes for tracing the outlines of irregular figures, for example, the shape of the tread of the human foot.

The object of the invention is to provide a scribe that will accurately trace either irregular or regular closed figures by a forward stroke and, as an ancillary object, one that may be controlled by one hand of the user.

Accordingly a feature of the invention resides in the provision of a pair of arms, each having provision for holding a pencil or other marking medium, and so connected that as the pencils simultaneously trace different sides of the object of which an outline is to be secured, they will automatically follow the contours and portray an accurate copy.

A further feature of the invention consists in the construction and arrangement of the pencil holders relatively to their supports, or arms of the scribe which hold them, permitting the pencil points to travel beneath an overhung side of the object being traced.

Another important characteristic of the invention is found in the provision of means for setting the two pencils to a like or to a differing angle relatively to the plane of their supports. This is particularly advantageous in the use of the scribe for tracing the outlines of the tread 30 of the human foot for the accurate fitting of shoes.

To the accomplishment of these objects and such others as may hereinafter appear, as will readily be understood by those skilled in the art, the invention comprises the features and combinations of parts hereinafter described and then particularly pointed out in the appended claims.

The nature and scope of the invention will best be understood from a description of the preferred embodiment thereof and the manner of its use 40 illustrated in the accompanying drawing, in which:

Figure 1 is a view illustrating the scribe in perspective while being used to trace the tread 45 of a human foot, the picture of the foot being broken away to show the purpose of an angular setting of the scribing pencils;

Fig. 2 is a view of the scribe in side elevation; and

Fig. 3 is another view of the scribe in the act 50 of starting the tracing of the tread of a human foot, in this instance viewed from the heel which is shown partly in cross section. In Figures 2 and 3 the scribe is shown as provided with means 55 of adjustment for angularity of the pencils.

In the embodiment of the invention illustrated in Figs. 1 and 2 of the drawing the scribe consists essentially of a double armed drawing tool one arm 10 being conveniently extended to form a handle 11 and the other arm 12 being pivoted at 13 on the arm 10 at the inner end of the handle. Each arm is bowed sufficiently for clearance 5 of any protuberances on the peripheral walls of the object being traced and also to permit a clear view of the object while the tool is being used. 10

The outer ends of the two arms are alike and a description of one will suffice for both. Referring to the arm 12, which preferably is of strip material, its outer end is bent downward relatively to the plane of the arm itself as at 14 and then directed inward forming a downwardly and inwardly directed end section 15. The tip of this section may be rolled upon itself to form a cylindrical holder 16 through which a pencil 17 may be passed and held firmly by frictional engagement. The axis of the pencil holder 16 is oblique to the plane of the arms of the scribe and, in ordinary use, to the plane of the paper 18 on which the outline is to be traced (see Figs. 1 and 3). 20

Where there is no provision for adjusting the obliquity of the pencils the angle of the pencil holders 16 is set at about 45° to the plane of the scribe arms (see Fig. 1) and this angle has been found to be right for setting the pencil points 30 under the overhang above the tread of the sides of the human foot in tracing an accurate outline of its tread, an operation incident to correct shoe fitting according to a newly developed system for which the scribe has been especially designed. 35

It may be desirable to set the pencils at other angles. Accordingly, as shown in Figs. 2 and 3, the pencil holder 19 is formed of a separable piece having a perforated ear 20 through which it is pivotally attached, as by a frictional rivet 21, to the flat tip of an inclined end section 22 on the scribe arm formed as hereinbefore described. An indicator and scale, see 23, Fig. 3, may be provided for adjustment of the angularity of the pencils to the same or to different angles as may 40 be desired. 45

The two arms 10 and 12 are normally drawn toward each other by a relatively light contractible spring 24 and a stop 25 is conveniently secured to the top face of the arm 12 for preventing the pencil points from engaging when the scribe is not in use. 50

A description of the manner of using the scribe in tracing the outline of the tread of a human foot, as illustrated in the drawing, will 55

suffice to apprise those skilled in the art of its other uses. The foot, either bare or stockinged, is placed on a sheet of paper, thin cardboard, or the like with the weight of the body thereon and, 5 for accuracy, with a form of support beneath the paper, as indicated in Fig. 1, that compensates for the shoe heel so that the body weight will spread the foot just as it does against the insole of a shoe on the foot. The scribe is opened and 10 initially set with the two pencils 17 at each side of the heel and about opposite the point beneath the heel that would be determined by the rear end of an insole when the foot is in a shoe (see Fig. 3). Then, by drawing the scribe forward 15 (see Fig. 1) the spring 24 causes the pencils to open and close relatively to each other as they trace the curves from heel to toe of the foot. Because of the inward angle at which the pencils are set, they simultaneously enter beneath the 20 undercut shape of the sides of the foot and trace the two sides of the true tread of the foot or substantially the true outline of the insole that should be used for fitting that particular foot. When the forward movement causes the pencils 25 to reach the toe the spring draws them together to complete the outline desired to be portrayed on the paper. Without the true or accurate outline of the tread, such as may be produced with the scribe of this invention, only a less accurate fitting of shoes may be had with an accompanying 30 loss of comfort to the wearer of the shoes.

While the features of the invention have been shown and described in their preferred embodiment, it will be understood that the invention 35 may be embodied otherwise than as shown in the drawing and described in the specification and yet be within the scope of the following claims.

What is claimed as new, is:

1. A scribe comprising an oppositely disposed 40 pair of outwardly bowed arms formed of strip material, pivoted together at one end with their faces in substantially the same plane, each of said strips being bent downwardly and then inwardly at its free end and finally twisted to set 45 their faces substantially perpendicular to the general plane of said two arms, a holder at each twisted end adapted to receive a marking pencil, said holders being set at diverging angles such that marking pencils carried thereby are directed downwardly and inwardly relatively to each other.

2. A scribe according to claim 1 having a contractile spring connecting said two arms between the pivot and pencil holders.

3. A scribe according to claim 1 having a contractile spring connecting said two arms between the pivot and pencil holders and means for preventing contact of pencils in said holders under the arm closing influence of said spring.

4. A scribe having two opposed arms lying in substantially the same plane, so connected to each other at one end that either may move independently of the other in said plane, and a marking pencil holder at the free end of each arm, said holders being so constructed and arranged that the pencils therein will point inwardly each toward the other in a plane sub-

stantially perpendicular to the general plane of said two arms.

5. A scribe according to claim 4 having the marking pencil holders each adjustably mounted on its supporting arm to vary the said obliquity 5 of the pencils carried thereby.

6. A scribe for tracing the outline of the base of an irregularly shaped object having overhung side walls comprising a pair of oppositely disposed, outwardly bowed arms pivoted at one 10 end for movement toward and from each other in substantially the same plane, a marking pencil at the free end of each arm lying in a plane substantially normal to the general plane of said arms and each pencil being canted inward 15 in said plane, and means, while said pencils are at opposite sides of said object, for yieldingly drawing them together providing for a simultaneous tracing of both sides of the base of the object by a single forward stroke of the scribe. 20

7. A portable hand scribe having two oppositely disposed marker supports pivotally mounted at one end, and each having a marking pencil at its free end, each pencil standing in a plane oblique to the general plane of said supports 25 the oblique stand of one pencil being the reverse of the other so that together they form a V with its apex at the pencil points, yielding means applied to said supports acting normally to maintain said supports closed, and a handle at 30 the pivoted ends of said supports through which a user may cause the oblique pencils to trace an accurate perimetral outline of an object of irregular form having overhanging side walls placed between said supports. 35

8. A portable hand scribe comprising a pair of marker supporting arms outwardly bowed to receive between them an object of irregular form, said supports being pivotally mounted at one 40 end and each carrying a marking pencil at its free end, yielding means connecting said two supports, acting normally to draw them together, means intermediate the two arms forward of their pivotal mounting forming a stop to be engaged by an arm and prevent breakage of 45 the pencils by contact when the scribe is not in use, and a handle at the pivoted ends of said supports, said yielding means being lightly tensioned and permitting said marking pencils freely to move unequal distances laterally toward 50 and from each other while tracing the irregular form of said object as the user draws them past its perimetral surface by said handle.

9. A portable hand scribe comprising a pair of opposed arms and a handle all in substantially the same plane, at least one of said arms being pivoted on the handle permitting opening and closing movements thereof, a contractile spring connecting said arms, means to limit the closing movement thereof, and a marking pencil at the 60 free end of each arm, each pencil pointing downward from its supporting arm, the axes of said pencils being at diverging angles such that each is directed inwardly toward the other enabling them to underlie overhanging walls of an object 65 of irregular form situated between said arms.

ERNEST E. DOANE.
